UNITED STATES PATENT OFFICE.

ARTHUR EDWARD STROUD, OF LONG EATON, ENGLAND.

LOOM.

1,357,127.

Specification of Letters Patent. Patented Oct. 26, 1920.

Application filed July 24, 1917. Serial No. 182,532.

To all whom it may concern:

Be it known that I, ARTHUR EDWARD STROUD, a subject of the King of Great Britain, and a resident of Long Eaton, in the county of Derby, England, have invented 5 new and useful Improvements in Looms, of which the following is a specification.

This invention relates to improvements in vertical looms provided with a number of shuttles working in parallel planes which are 10 at right angles to the width of the loom and used for the production of tapes, ribbons, and similar articles, and has reference to looms in which the shuttles, together with 15 their carrying and actuating mechanisms move vertically with the reed.

The present invention has for its object 20 improvements in the construction and arrangement of the means for and in the method of carrying and actuating the shuttles, improvements in the construction of the 25 reed, improvements in and relating to the thread tension and let-off mechanisms, improvements in the work take-up mechanisms, and improvements in the general construction 30 and arrangement of the loom.

In the accompanying drawings:—

Figure 1 is the end elevation of a loom constructed according to this invention.

Fig. 2 is a plan of the driving mechanism.

Fig. 3 is a transverse section of the loom.

Fig. 4 is a plan of the warp bobbin and the connected thread let-off and tension mechanisms.

Fig. 5 is a transverse section of the central frame showing a shuttle and associated parts.

Fig. 6 is a plan of the same.

Fig. 7 is a plan of the improved reed.

Fig. 8 is a transverse section of the same.

Fig. 9 is a side elevation of the shuttle.

Fig. 10 is a transverse section of the same.

Fig. 11 is a longitudinal section of the central frame, parts of the machine being 45 broken away.

Fig. 12 is a bottom plan view of the parts shown in Fig. 11.

The central frame of the improved loom 50 comprises a front bar 1, a back bar 2, and end connecting brackets 3 upon and to which the bars 1 and 2 are attached. The brackets 3 are attached to rods 4 which are fitted to slide in guides 5 carried by the standard 55 6 and are actuated through connecting rods 7 by crank pins 8 carried by eccentric toothed gear wheels 9 which are driven by similarly

shaped wheels 10 on the driving shaft 11, the said wheels being so arranged that the brackets 3 and the parts connected thereto are moving at their fastest speed when the 60 brackets are approaching and leaving their highest position and the reed is beating up the wefts. The central frame is also provided with springs 12 by which the weight of the vertically moving parts is wholly or 65 partially balanced.

Attached to the upper surfaces of the bars 1 and 2 there are carrying and bearing plates 13, Fig. 5, for the shuttles 14, and such plates are preferably of multiple ply wood 70 by which lightness and an approximately true surface is obtained. The shuttles 14, Figs. 9 and 10, which are preferably made of aluminium, carry a weft spool 15 which is free to rotate upon a horizontal axle 16 and 75 is held from accidental rotation by a brake device 17. The thread 18 passes from the spool 15 under a fixed wire 19 to an eye 20, and then to the spring 21 by which the slack of the thread is taken up, and the thread 80 leaves the shuttle by the central eye 22. The sides of the base of the shuttle are parallel and the shuttles slide upon the plates 13 between strips 23, Fig. 6, attached to such plates, the said strips forming spacing pieces 85 and side guides for the shuttles.

The shuttles are positively traversed through the sheds by a front driving blade 24 and a back driving blade 25 which are 90 of wood attached to metal tubes 26. These tubes are fitted with end and intermediate arms 27 which are pivotally connected to bow levers 28 on the rocking shafts 29 which are carried in bearings 30 from the bars 1 and 2. At both ends of the shafts 29 there 95 are actuating levers 31 the axles 32 of which engage with slots in intermediate levers 33 mounted upon axles 34 fixed upon the standards. The lower ends of the levers 33 are connected by links 35 to cam levers 36 which are fulcrumed at 37 and actuated by cams 38 on short shafts 39 which are driven at half the speed of the shaft 11 by toothed gear pinions 40 and wheels 41. The ends of the tubes 26 are provided with rollers 42, Figs. 5 and 6, which run upon lower cams 43 fixed to the bars 1 and 2, and to prevent the driving blades being accidentally raised clear of the shuttle driving noses 44, Fig. 9, there is a fixed upper cam 45 in connection 110 with the back blade 25, and a movable upper cam 46 in connection with the front driv-

ing blade 24, this latter being made movable so that the front blade can be raised by hand to allow of the shuttles being inserted and withdrawn. The front cam 46 is fitted to 5 slide to and from the roller 42 in a guide bracket 47 and is held in its working position by springs 48 mounted upon axles 50^a which project through the bracket 47 and at their outer ends are connected by an axle 49^a 10 upon which a roller 49 is mounted. Working in connection with such roller there is a cam 50 on a vertical shaft 51 and this cam is long enough to allow for the vertical movement of the roller 49 as it rises and 15 falls with the central frame. The shaft 51 is carried in fixed bearings 52 and at its lower end is fitted with a toothed wheel 53 which gears with a toothed rack 54 on the power rod 55, these parts being so arranged 20 that when the belt is moved on to the loose pulley the cam 46 is drawn back clear of the roller 42 to allow of the front blade being raised clear of the shuttles 14. Referring to Figs. 11 and 12 for an understanding of the 25 arrangement and operation of these parts it will be seen that when the fork 55^a carried by the power rod 55 is actuated to move the drive belt 56^a from the fixed pulley 57^a to the loose pulley 57^b, the rack 54 engages 30 with and rotates the toothed pinion 53 and rotates the shaft 51 carrying such pinion. In rotating the shaft 51, the cam 50 bears on the roller 49 and actuates, through the axles 50^a, the front cam 46, to slide such cam 35 within the bracket 47. The axles 50^a are connected to the cam 46, and the transverse axle 49^a, connecting the axles 50^a, and supporting the roller 49, is adapted to slide in guides 51^a. 40 Similarly when the belt 56^a is moved from the loose pulley 57^b to the fixed pulley 57^a the shaft 51 is rotated in the opposite direction, through the gearing 53 and 54, the cam 50 ceases to bear on the roller 49, and the 45 front cam 46 is moved, under the action of the springs 48, to assume the position shown, holding the front blade in normal position. The shuttle driving mechanism is so arranged and timed that when the shuttles are 50 in their central position as shown in Fig. 5, they are engaged by both driving blades 24 and 25. As the shuttles are moved toward the front of the loom by the front driving blade 24, the back blade 25 is raised by the 55 cam 43 clear of the back noses of the shuttles and then comes to rest. The front blade then completes the movement of the shuttle and pulls them through the sheds at which time the central frame is at or near its highest position and rests until the weft threads have been beaten up and new sheds formed 60 when the shuttles are pushed into such new sheds by the return stroke of the front blades. When the shuttles are near their 65 central position again and the central frame

is approaching its lowest position both driving blades are moving in the same direction and at the same speed and continue to so move until the front blade has been raised clear of the shuttle front noses and the back 70 blade lowered into the shuttle back noses after which the front blade comes to rest. The shutters are then operated by the back blade and in subsequent motions the shuttles are moved into and out of the sheds by 75 the front and back blades alternately.

The warp threads 56 for each piece of fabric are carried by a separate spool 57, Figs. 3 and 4, and such spools are arranged in groups and fitted to rotate in slotted 80 bearings on the uprights 58 attached to a lower rail 59 and an upper rail 60. Each spool carries all the threads required for each piece of fabric and these threads pass from the spool over a roller 61, under a 85 roller 62 mounted in the weight 63 and over guide rollers 64 and 65 to a tube 66 at the lower part of the loom. The threads then pass upward to a wire work slay or guide 67 in which they are separated and arranged 90 in rows at right angles to the width of the loom. From this slay they are conducted to and threaded through holes in the shed forming thread guide bars 68 which are thin steel bars having at least one hole for each 95 piece of fabric made at the same time and there are at least the same number of bars as there are threads in each piece of fabric. At one end of the loom the ends of the bars 68 are connected to springs which tend 100 to hold the bars at one end of their movement, and the other ends of the bars, at the opposite end of the loom, are connected to a jacquard or equivalent pattern mechanism, by which the bars are actuated to 105 form the sheds according to the requirements of the fabric and in accordance with any of the usual methods. The threads pass upward from the bars 68 through the reed 69 to the work take-up mechanism herein- 110 after described. Each flange of the spools 57 is grooved for a brake cord 70, one end of which is attached to the uprights 58 and the other end to a light frame 71 which is pivotally mounted upon the uprights 58 and 115 provided with springs 72 by which the cords 70 are held in braking tension upon the spool flanges. As each piece of work is made and taken up the weight 63 on the threads making a piece of fabric is raised 120 into contact with its frame 71 until the tension on the brake cords 70 is sufficiently reduced to allow of the weight pulling a length of thread off the spool. The weight then descends and the springs come into 125 action again and hold the spool stationary. The reed 69, Figs. 7 and 8, is built up of side pieces 73 which are connected together at intervals by cross bars 74 there being one cross bar to every one or more pieces of fab- 130

- ric made and the least distance between which is large enough to allow of a shed being formed between them. Mounted upon the cross bars 74 there are helically coiled 5 springs 75 the pitch of which is in accordance with the gage of the fabric to be made. The reed wires 76 extend the full width of the reed and the ends of such wires are carried by end pieces between the side pieces 10 73. These wires are laid upon the cross bars 74 between the coils of the springs 75 or are threaded through such coils, and inside the springs and over the reed wires there are cross wires 77 which prevent accidental 15 lifting of the wires. By this method of construction the reed wires are accurately and flexibly spaced and are free to move sidewise to allow of irregularities in the threads passing between such wires and the 20 wefts in all the fabrics made are simultaneously beaten up by the same wires. The complete reed is fixed between the edges of the plates 13 and is supported upon strips on the underside of such plates or upon 25 the bars 1 and 2.
- Each piece of fabric as it is made passes partially over the upper part of a roller 79 and partially under the lower part of a second roller 80, by which means the fabric is 30 held straight at the beat up position. The rollers 79 and 80 are adjustably carried in a bar 81 so that their relative positions can be varied according to the requirements of the fabric. After the fabrics leave the rollers 80 they are given a quarter twist and pass upward over a fixed rod 82 and then downward and under the take up roller 83. The surface of this roller is covered with emery or is otherwise suitably roughened 35 and the roller is positively driven by a toothed worm wheel 83^a, Fig. 1, worm 84 and ratchet mechanism 85, the pawl or clawker of which is carried by a lever and actuated by an eccentric 96 on the 40 shaft 11. In connection with the work take-up roller 83 there is a separate press roller 87 for each piece of fabric and such rollers hold the fabrics in frictional driving contact with the surface of the roller 83. The fabrics 45 pass from the take-up roller 83 to the dividing rod 88 and all the odd numbered fabrics pass from this rod to bobbins or creels 89 at the front or back of the loom and all the even numbered fabrics to bobbins 50 or creels at the back or front of the loom. Each bobbin or creel is separately driven from rollers 90 by flexible bands 91 which may be endless coiled springs and must be capable of maintaining the necessary tension 55 upon the fabrics and of slipping when not actually rotating the bobbins or creels. The rollers 90 are carried in end bearings and are driven by a toothed chain wheel 92 on the axle of the take up roller 83 through 60 an endless chain 93 and chain wheels 94.
- The loom is also fitted with fast and loose driving pulleys and suitable bell fork gear, and is provided with hand wheels 95 which are geared to the driving shaft 11 by bevel toothed wheels 96 and inclined shafts. 70
- I claim:—
1. In a narrow ware loom the combination of the shuttles, a central frame carrying the same, means for guiding the frame vertically, cranks and connecting links for actuating the central frame and eccentric toothed gear driving wheels for driving the central frame, through the said cranks and connecting links at a varying speed substantially as herein set forth. 80
  2. In a loom for weaving a plurality of narrow fabrics in parallel planes at right angles to the width of the loom, the combination of a central frame carrying the shuttles and reeds, means for guiding the frame 85 and means for moving the frame along the guides toward and from the completed fabrics, including eccentric driving gears arranged to move the frame at its fastest speed as the reeds are brought into operation to 90 beat up the weft threads.
  3. In a loom for weaving a plurality of narrow fabrics in parallel planes and at right angles to the width of the loom, the combination of a supporting frame, a vertically movable central frame mounted therein, shuttles supported by the vertically movable frame, reeds also supported in the movable frame, drive bars for reciprocating the shuttles back and forth through the shed, levers supported in the vertically movable frame for operating the driving bars and driving levers on the stationary frame having sliding connection with the levers that operate the driving bars, arranged to cause 95 100 the most rapid movement of the shuttles as the central frame is raised and just before the reeds come to position to beat up the weft threads. 105
  4. In a narrow ware loom the combination of the central frame, means for guiding and actuating the same, shuttles carried by the frame, driving blades for positively traversing the shuttles, end cams for controlling the vertical position and movement of the 110 driving blades, arms fixed to the said blades, bow levers to which the blade arms are jointed, rocking shafts carrying the bow levers, cams for driving the shuttle blades and levers, links and slotted connections between 115 the cams and the rocking shafts substantially as herein set forth. 120
  5. In a narrow ware loom the combination of the central frame, means for guiding and actuating the same, the shuttles carried by the central frame, the shuttle driving blades, means for positively moving the driving blades to and from the center of the loom, means for periodically and alternately moving the blades vertically rela- 125 130

- tively to the central frame to cause one of them to disengage the shuttles while the other completes the driving movement, a reed frame carried by the central frame, and 5 shed forming thread guide bars substantially as herein set forth.
6. In a loom for simultaneously weaving a plurality of narrow fabrics, the combination 10 of a central frame carrying the shuttles and reeds, means for guiding and actuating the same to cause the reeds to beat up the wefts, reciprocating shuttle-driving blades for causing the traverse of the shuttles, one driving blade having engagement with the shuttles 15 at the front and the other at the rear, means for giving to each blade a positive movement to actuate the shuttles through approximately half their traverse, and means for positively disengaging one blade from the 20 shuttles and arresting its movement after it has caused approximately one-half the traverse of the shuttles and at the same time causing the other blade to engage with the shuttles and complete their traverse, and for 25 alternately repeating these operations.
7. In a narrow ware loom, the combination 30 of a central movable frame, means for guiding and actuating the same, shuttles supported in the movable frame, driving blades having separable engagement with the shuttles, one at the front and the other at the rear, fixed cams for guiding the rear driving blade to cause it to disengage from the shuttles as they reach approximately their mid 35 position when moving in one direction and to engage with the shuttles when reaching approximately the same position when they move in the opposite direction, cams acting on the front driving blade for causing it to have similar engagement with and separation from the shuttles, the cams for the front driving blade having movable parts and means for moving such parts of the said cams and carrying them out of action when the loom is stopped to permit the removal 40 of the shuttles.
8. In a narrow ware loom the combination 45 of the central frame, means for actuating the same, the shuttles, the shuttle driving blades, bow levers on rocking shafts for actuating the blades, operating levers fixed upon the rocking shafts, slotted levers on stationary axles for oscillating the rocking shafts, and cams, levers, and connections for actuating the slotted levers substantially as 50 herein set forth.
9. In a narrow ware loom the combination 55 of the central frame, the parts carried by it and moving vertically with it, the thread guide bars, cranks and connections for driving the central frame, eccentric toothed gear wheels carrying the cranks, eccentric toothed gear wheels driving the crank carrying wheels, cams for actuating the driving blades and toothed gear wheels driving the said 60 cams substantially as herein set forth.
- ARTHUR EDWARD STROUD.
